METHOD OF AND APPARATUS FOR OPERATING INTELLIGENCE SYSTEMS

Elmer L. Greensfelder, Baltimore, Md.

Application January 2, 1931, Serial No. 506,111

10 Claims. (Cl. 197—6.1)

This invention relates to improvement in method of and apparatus for operating intelligence systems for enabling the blind to read ordinary newspapers, books, hand writing, cartoons, sketches, etc., and comprises a method for accomplishing the foregoing together with improved instrumentalities for carrying out said method.

An object of the invention is to provide a simple device adapted to scan a page or other printed or written matter to be reproduced and to simultaneously reproduce the same in a series of dents or raised perforations forming letters, words, etc. on a second sheet of paper, or on a pin board by means of raised points.

Another object is to provide a device adapted to reproduce letters, words, etc. of greater dimension than the originals.

Another object is to provide a scanning unit containing an exciting lamp and a light sensitive cell in fixed angular relation to each other.

Still another object is to provide an electrically operated recording means adapted to record on a receiving medium or record such as a sheet of paper or the like. All moving parts associated with said means may be automatic or manual.

Other objects will be obvious to those skilled in the art upon perusal of the specification and appended claims.

The invention is based on the method of reading letters and words in relief by the blind with the finger tips, and by means of this invention enlarged images in relief on a second sheet of paper are reproduced from printed or written pages to be read.

Hereinafter the sheet containing the printing, writing or sketches to be read, will be referred to as the "page" and the sheet upon which the "page" is reproduced or recorded in relief will be referred to as the "record". These records are permanent and may be filed away to be re-read or they may be passed on to other blind readers.

The preferred method consists in automatically scanning the page to be read with a narrow beam of light which strikes the page preferably at an angle. A light sensitive cell is so positioned in relation to the scanning beam that it receives the reflected light from the page, this position being substantially equal and opposite to the angle of the beam of light. The exciting lamp for furnishing the beam of light is connected to a source of current and a switch is provided to control the same.

The light sensitive cell is connected to an

amplifier and/or relay or other suitable device for controlling a magnetic switch which in turn operates a punching mechanism.

Every time the electro-magnet releases the armature of the switch, a circuit is completed through the punching device and a source of current, causing the arm carrying the punch to pierce, perforate or preferably make a dent in the record.

The punching mechanism and the scanning unit move in fixed relation to each other; however it is preferable that the path of travel of the former be greater than the latter so that the raised reproduction will be substantially larger than the original matter on the page being scanned.

When the beam of light falls on a white portion of the page being scanned the light is reflected therefrom to the light sensitive cell and current flows and via the amplifier energizes the electro-magnets of the switch attracting the arm thereof and thereby opening the circuit controlling the punching device, and this circuit is open as long as the light beam is scanning the white page.

As soon as the light beam falls on a dark portion of the page, such as type, handwriting, etc., no light is reflected to the cell and the current supplied the electro-magnets of the switch is reduced below a certain minimum, the armature of the switch is released and it moves by gravity, or otherwise, to its normal position, establishing a circuit in the punching device and causing the arm or hammer carrying the punch to strike the record and make a raised dot or perforation therein.

As the scanning unit traverses the page the hammer is actuated every time the light beam falls upon a dark spot, and as the scanner and the punching device are moved in a fixed relation to each other the result is a series of raised dots or perforations in the record comprising enlarged raised images of the matter on the page.

The scanning device preferably "slices" the type to be scanned, and the beam of light traversing the page horizontally would make several trips across in reproducing a line of type on the paper record, moving down a short distance after each trip across the page.

Referring to the drawings:—

Figure 1 is a view partly in perspective and partly diagrammatic showing an arrangement of the device;

Figure 2 is an end view of the paper record carrier and its relation to the circular platen;

55

Figure 3 is a modification of the arrangement shown in Figure 2;

Figure 4 is a view, partly in section, of one form of the scanning device;

5 Figure 5 is an enlarged cross-section of a portion of the paper record showing several forms of raised dots, perforations, etc.;

10 Figure 6 is diagrammatic, showing the preferred path of travel of the scanning unit and the punching mechanism relative to the page and the record, and

Figure 7 is an enlarged top view of the hammer showing a toothed wheel substituted for the needle.

15 A source of light 10 which will hereinafter be referred to as an exciting lamp is mounted in a suitable socket 11 in a casing 12. This casing is supported on an arm 13 of any suitable shape at an angle to the vertical central stem 14. The 20 opposite end of the arm 13 carries a second casing 15 suitably inclined at an equal and opposite angle to the vertical stem 14.

The second casing 15 has mounted therein a light sensitive cell 16 in a suitable socket 17.

25 In the scanning device, Figure 4, the casing 12 may be provided with a lens 18 in a suitable holder 19 which may be moved in the casing to bring the light rays 21 to a focus on the page 20. This lens 18 may be single or multiple as desired, or 30 suitable reflectors may be substituted therefor, the result being to bring the light rays 21 to a focus on the page. Likewise a lens 22 in a suitable holder 23 may be adjustably mounted in the casing 15, for gathering the reflected light 21a 35 and passing the same on to the cell 16. The lenses are locked in position on assembly. It has been found that the cell 16 works very well without the lens 22, so in some cases it may be omitted.

40 In some cases it may be desirable to extend the casings 12 and 15 to a point nearer the page or even in contact with it, in which latter case outside light would not interfere with the operation of the scanning device.

The central stem 14 is hollow and carries on its 45 lower end a presser foot 25 having a slot or opening 26 therein for the beam 21 to pass through. A rod 24, secured to a nut 29, extends into the hollow center of the stem 14 and a spring 27 therein serves to press the scanning unit downward 50 with the presser foot 25 in contact with the page 20. The downward travel of the scanning unit may be limited by a slot in the stem 14 and a pin in the rod 24 (not shown) if desirable.

55 A threaded rod or lead screw 28 engages the nut 29 which is secured to the arm 13 and as this threaded rod 28 is rotated the nut 29 propels the scanning device across the page 20.

60 Terminals 30 are provided for the exciting lamp 10 and wires 31 lead therefrom to a source of current 32 and a switch 33.

The light sensitive cell socket 17 is provided with terminals 34 and wires 35 lead therefrom to a suitable amplifier unit 36 at 37. The wires 65 38 leading from an external source of current connect to the amplifier at 39. In some cases with certain types of light sensitive cells it may be necessary to use a relay in connection with the amplifier, but in such cases the relay may be 70 built into the amplifier unit.

A magnetic switch designated generally by the 75 numeral 42 has electro-magnets 43 and 44 connected by wires 41 to the output terminals 40 of the amplifier 36. When current flows through the windings of these electro-magnets 43, 44,

an armature 45 is attracted and held in the position shown in solid lines, Figure 1. A member 46 is attached to this armature and carries contact points 47, 48.

When no current flows in the windings of the electro-magnets 43, 44, that is when the beam of light 21 falls on a dark or black portion of a letter on the page 20 and no light is reflected to the cell 16, the armature 45 is released and falls down with the member 46 assuming the position shown dotted as 46a whereupon the contact point 47 contacts with a point 49 and the point 49 makes contact with the point 50.

Wires 51 form a circuit including these contact points aforementioned, a source of current 52 and a punching device or hammer unit designated by the numeral 58. A switch 53 is also included in this circuit so that it may be opened and the circuit broken when the device is not in use.

The preferred form of punching unit or hammer device 58 consists of a casing 54, which has a hollow threaded portion membering up with a threaded rod or lead screw 60 and contains electro-magnets (not shown) adapted to actuate an arm 55, the outer end of which carries a hammer 56 with a needle or punch 57 supported thereon. This electro-magnet may be arranged so that the hammer makes a single stroke upon the completion of the circuit, or it may be arranged to vibrate the hammer.

The normal position of the hammer 56 is shown in solid lines Figure 2, and its striking position is shown in dotted lines.

The record 61 may be made of paper, thin metal or any other suitable material and preferably handled in the form of a roll so that it may be readily moved through the device, is carried on a shaft 62 and passes between rollers 63, 65 and a platen 64, and on to a take up shaft 66.

The lead screw 28 which propels the scanning device across the page 20 is inter-connected by gearing or other suitable driving means to the lead screw 60 which propels the hammer mechanism 58 across the record 61, and as the hammer mechanism 58 must move a greater distance than the scanning mechanism to enlarge the record, the ratio of the threads on the respective lead screws may give this result or the threads on the lead screws may be the same and the gearing between these lead screws may give the desired ratio.

The lead screw 28 is provided with a gear 78 and the lead screw 60 is provided with a gear 79. A shaft 80 is provided with a worm 81 meshing with the gear 78 at one end thereof, and a worm 82 at the other end thereof, meshing with the gear 79. The shaft 80 also carries a gear 83 which meshes with a worm 84 carried by the shaft 85. The shaft 85 is connected to the motor shaft 86 by means of a flexible coupling 87.

The motor 88 may be provided with terminals 89 which lead to its armature and terminals 90 which lead to its field windings.

A solenoid 91 actuates a pawl 92 which in turn moves the ratchet wheel 93 forward one tooth. This ratchet wheel is secured to a shaft 94 which carries feed rollers 95 and 96. These feed rollers engage the page 20, and rollers 97 and 98, positioned above the page, retain the same in engagement with the feed rollers 95 and 96.

A solenoid 99 actuates a pawl 100, which in turn moves the ratchet wheel 101 forward one tooth. The ratchet wheel 101 is secured to a shaft 102 which carries feed rollers, one of which is

shown at 103, for feeding the record 61 step by step past the hammer unit 58. Suitable rollers, one of which is designated by the numeral 104, may be provided for maintaining the record in contact with the feed rollers 103.

The gears 78, 79 and 83 and the worms 81, 82 and 84 may be spiral or helical gears adapted to drive the lead screws 28 and 60 in the same direction.

10 Contact arms 105 and 106, positioned in the path of the nut 29 at one end of the lead screw 28, and contact arms 107 and 108, positioned in the path of the nut 29 at the other end of the lead screw, are provided for energizing the solenoids 15 in order to make the effective path of the scanning unit and of the hammer unit similar to the path illustrated in Figure 6.

The contact arm 105 and the contact arm 108 are connected together by a wire 109 and are in 20 turn connected to one end of the solenoid 99 via the wire 110. The other end of the solenoid is connected via a wire 111 to one end of the solenoid 91. The other end of the solenoid 91 is connected via a wire 112 and a wire 113 to the negative side of the source of current 52.

The contact arms 106 and 107 are connected in common by a wire 114 and to one side of the switch 53 by means of wires 115 and 116 so that with the switch 53 closed, the closing of the contact arms 105 and 106 or the closing of the contact arms 107 and 108 will energize both solenoids. With the nut 29 of the scanning unit moving to the right, as shown in the top line of Figure 6, contact arms 107 and 108 will be closed and both 35 solenoids will be energized and the record 20 will be caused to move one step, at which time, under control of the solenoid device, the current of the motor 88 is reversed, thereby reversing the motor. This reversal may be accomplished as follows:

A disc 117 is provided with a plurality of metallic inserts, one of which is designated by the numeral 118, there being one insert for each tooth in the ratchet wheel 93. Every other insert 118 45 is connected to a collector ring 119 and those inserts between are connected to a collector ring 120.

The collector ring 119 is energized by current 50 passing from the negative pole of the battery 52 via the wire 113 and the brush 121. The other collector ring is fed from the positive terminal of the battery 52 (when the switch 52 is closed) via the wire 122 and the brush 123.

A brush 124 makes contact with one of the inserts 118 and a brush 125 makes contact with an adjacent insert 118. The brushes 124 and 125 are connected to the field winding terminals 90 of the motor via wires 126 and 127 respectively.

By this arrangement, the current through the 60 field of the motor is reversed each time the ratchet wheel is moved forward one tooth. The brush terminals 89 of the motor 88 are connected to the source of current 52 (when the switch 53 is closed) by means of wires 116 and 128.

65 Due to the closure of the contact arms at each end of the travel of the nut 29, the line of travel of the light beam in scanning the page is from left to right, then from right to left, etc., as shown diagrammatically in Figure 6, and the same relative travel obtains with the hammer mechanism with respect to the record. It is obvious that this 70 relation may be reversed and the mechanism may be stationary and the page and record may move in respect thereto.

75 The scanning device traverses the page from

right to left, then from left to right, etc. and makes several trips across the page in scanning a complete line of type and the number of trips across per line varies with the size of the type.

When the light beam 21 falls on a white portion of the page 20, reflected light 21a falls upon the active elements of the cell 16, current flows in the wires 35 to the amplifier 36 and the amplified current, via the wires 41, energizes the magnet 44, 43 and the armature 45 is attracted thereto. 10 Since the contacts 47, 49 and 48, 50 are open, no current flows in the hammer circuit, and the armature is held in this position as long as a white portion of the page is under the light beam 21.

15 As soon as a black or dark portion of a letter or mark on the page 20 passes under the beam 21, no light is reflected to the cell 16 so no current flows via the amplifier 36 to the magnets 43, 44, so the armature 45 falls, closing the contacts 20 47, 49 and 48, 50, whereupon current flows in the hammer circuit and the hammer 56 moves forward causing the punch 57 to make a dent or perforation in the record 61 against the platen 64.

In cases where the hammer is made to vibrate 25 when its circuit is closed, a wide black space on the page will make a series of dents closer together.

Instead of having the hammer vibrate it may sometimes be desirable to have a wheel 57a having a number of teeth 57b pivoted at 57c on the hammer 56, in which case when the hammer is held forward against the record 61 due to a substantial length of black on the page, the wheel 57a will rotate and the teeth 57b will make a 30 series of dents in the record.

The shape of the end of the punch 57 may be made blunt to push a dent in the record as shown at 35 (Figure 5), or it may be made sharp enough to pierce the record as shown at 16.

The record may be read while it is in the machine and a plate 67 (Figure 3) may be provided to back the record up as the reader passes his fingers over the same. It is obvious that a long scroll of record can be produced and after being read by one person it can be passed along to others.

It is also obvious that various colors of light 45 may be used, and that the "pages" of material to be reproduced may be white or of any color, and 50 where the print is only on one side of the paper the scanning beam could be on one side thereof and the cell could be on the other side just so they are in fixed relation to each other.

The hammer unit 58 could be arranged so that 55 the punch 57 would strike the record 61 when the light beam 21 shines on white parts of the page by arranging the magnetic switch 42 so that when the armature 45 is attracted the contacts 47, 49 and 48, 50 would thereby be closed instead of 60 open, and when a dark or black part of the page is scanned the contacts would remain open and no blow would be struck and the result would be, a record with all the surface raised except where the letters or words occur, in which case the 65 record could be read from the reverse side.

A multiplicity of cells, light sources, and hammer units could be used so that several lines could be simultaneously scanned and recorded thus speeding up the work.

The invention is not limited to scanning and recording horizontally as it is obvious that it could be done vertically and accomplish a similar result.

The page may be enlarged by projecting the 75

same or to a screen or ground glass by usual and well known methods, and have the scanning device scan the enlarged image of the page and if the projected image is the same size as the record 5 the lead screw for the scanning unit and the lead screw for the recording device would feed the respective devices forward at the same speed.

When the device is scanning the untyped space between two successive lines or ahead of or at the 10 end of a short line, the operator can feel or hear this wasted motion and save time by setting the scanning unit to the next line.

The paper or page is provided with a suitable holder (not shown) and the same is moved up as 15 the scanning progresses as described above.

The record is always moved up or shifted, in the direction of the arrow, through a greater distance than the corresponding movement of the page or the scanning unit, as this gives an enlarged reproduction vertically. 20

It is obvious that the scanning mechanism may be moved down (or up) step by step instead of having the page move as hereinbefore described.

An alternative means for carrying out the above 25 method would be to substitute for the paper record a pin board or cylinder containing many rows of raisable pins so arranged that those struck by the hammer device would rise to a higher level than those not struck, and remain retained in this 30 position by suitable locking mechanism. Thus when a page has been scanned, a series of pins corresponding to the type stands up above the level of the other pins and can be readily read with the finger tips. This is of course not a permanent record as the retaining device may be 35 actuated and the pins released, whereupon the device is ready to be used over again. This is akin to the erasing of writing on a slate or blackboard.

40 The motion of the scanning device across the page and the recording device across the record may be intermittent, similar to the motion of a typewriter carriage. In such arrangement the motion of these parts may be controlled by suitable escapements, the recording mechanism being moved by a larger escapement than the one moving the scanning unit. It may also be desirable in some cases to have the above devices move in one direction and reset them when the end of 45 the travel is reached.

Many variations can be made in the apparatus described without departing from the spirit of the invention.

I claim:

55 1. In combination, a page to be scanned, a scanning device adapted to be passed over said page, a lead-screw for propelling said device, a flexible record strip, a recording device including an impact tool adapted to be passed over said 60 record, and record matter therein in a series of raised perforations or dents, a lead-screw for propelling said last device, means between said lead screws to cause one of said devices propelled thereby to move a greater relative distance than 65 the other, means for moving said page and said record step by step at an angle to the movement of said devices between the operation thereof, and means cooperating with said last means for simultaneously reversing the rotation of said lead-screws therewith.

70 2. In a device of the character described, a movable scanner comprising a frame having a center column extending downwardly, a presser foot resiliently supported by said column, a light sensitive cell positioned on said frame, an excit-

ing lamp positioned on said frame in angular relation to said cell, a lens for said cell, and a second lens for said lamp, said lenses having a common focal point adjacent to said presser foot.

3. In a device of the character described, matter to be scanned, a scanning device movable relatively thereto, said device including a lamp and a light sensitive cell, means for focusing a beam of light from said lamp on a portion of said matter, means for concentrating reflected light from 10 said matter on said cell, a record sheet, and a round impact tool magnetically actuated under control of said cell and mechanically moved relative to said record sheet in timed relation to the movement of said scanning device. 15

4. In a device of the character described, matter to be scanned, a scanning device, means for moving said matter and device relative to each other, light sensitive means on said scanning device, a circuit including said light sensitive means 20 and an amplifier, a relay connected to the output circuit of said amplifier and a source of current, a record, and a recording device including a single impact tool mechanically moved relative to said record and electrically actuated under control of said relay for permanently recording said matter in the form of raised perforations or dents. 25

5. In combination, an object to be scanned, scanning means including a light sensitive element movably positioned relative to said object and arranged to be moved back and forth to scan the same, a flexible record sheet, recording mechanism movably positioned relative to said record and arranged to be moved back and forth in time 30 with the movement of said element to record in said record a series of raised perforations or dents in the same actual outline as matter on the object scanned, the path of movement of said recording mechanism being longer than that of said 35 scanning means, thereby producing a record larger than the object scanned. 40

6. In combination, an object to be scanned, a scanning device including an exciting lamp and light sensitive means fixed relative to each other 45 and movably positioned relative to said object and adapted to scan the same in parallel lines thereover, a circuit including said light sensitive means, recording means in said circuit controlled by said light sensitive means, record material and 50 means for supporting the same in operative relation to said recording means, means for moving said recording means in timed relation to the movement of said scanner device and means associated with said recording means to form a permanent flexible record comprised of a series of 55 raised perforations or dents discernible by touch in the same actual outline as matter on the object to be scanned.

7. In a device of the character described, a 60 page, a scanning device adapted to distinguish light and dark variations on said page, a flexible sheet, a punching mechanism adapted to be controlled by said scanning device, means for moving said scanning device back and forth over said page, means for moving said punching mechanism back and forth over said sheet in definite timed relation to the movement of said scanning device, and an amplifier adapted to amplify impulses in accordance with said variations and to deliver amplified impulses to said punching mechanism to produce indentations in said sheet, thereby producing on said sheet matter from said page in actually the same outline. 70

8. In a device of the class described, an object to be scanned, a scanning device including a light sensitive cell, an exciting lamp and a movable support, recording mechanism, a flexible metallic record, and means for simultaneously moving said scanning device and recording mechanism in definite timed relation to each other whereby a record composed of a series of raised perforations or dents in actually the same configuration as that of matter on the page to be scanned will be produced caused by the variations in color or intensity of light reflected from the object being scanned.
9. In a device of the character described, a page having matter thereon optically distinguishable from the page, a device including photoelectric means for scanning said page, a reproducing device and means connected to said devices to operate the same simultaneously in definite timed relation to each other to scan said page and to permanently reproduce in flexible sheet material raised dents corresponding to the optically distinguishable matter thereon, said dents being recognizable by touch actually in the same configuration as said optically distinguishable matter. 5
10. In a device of the character described, a scanning unit comprising a supporting frame, a source of light supported thereon, a light sensitive cell carried on said frame in fixed relation to said source of light, matter to be scanned, means including a member contacting with said matter for positioning said frame relative to said matter, means for moving said frame relative to said matter, and means controlled by said cell for recording in a flexible sheet representations of said matter in relief, said representations having the same actual form and outline as that of said matter. 10 15

ELMER L. GREENSFELDER. 20
